REFRIGERATOR CAR CONSTRUCTION

Charles D. Bonsall, Chicago, Ill., assignor, by
mesne assignments, to Standard Railway Re-
frigerator Company, a corporation of Delaware

Application January 8, 1940, Serial No. 312,851

18 Claims.

(Cl. 62—17)

My invention relates to refrigerator cars used to transport perishable commodities at a pre-determined temperature. The essential features of a refrigerator car are an insulated body to prevent or retard ingress of heat during warm weather and egress of heat during cold weather and a cooling means and a heating means to be used during warm and cold weather respectively.

My invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

My invention is particularly applicable to refrigerator cars of the hereinabove described overhead bunker type, having refrigerant containers which are wholly or partially imperforate so as to retain a certain amount of liquid within the container. The invention pertains particularly to valves adapted to drain the liquid from the containers either into the side wall flue or upon the drip pan, in which latter case the liquid drains finally into the side wall flue.

An object of the invention is to provide an operating means for the above mentioned draining valves, which means is operable from within the lading compartment of the car and may be operated without dismantling any part of the car.

Another object of the invention is to provide an operating means through which water can not fall upon the lading. Any apparatus involving moving parts, such as a handle for operating a valve, is necessarily subject to leakage around the moving parts. I prevent such leakage by disposing the moving parts above the level of the liquid upon the drip pan.

A further object is to provide means for operating the draining valve so as not to interfere with the flow of air within the car whether such air flow is for the purpose of refrigerating, ventilating or heating the car.

Another object of the invention is to provide

draining valves and operating means therefor so that the valves may be operated while the lading space of the car is filled. I provide such operating means within the center duct so that a man may operate the valves upon climbing on top of the load within the car.

A further object of the invention is to provide means by which the draining valve and the operating means therefor may be cleaned and repaired upon a minimum amount of dismantling of the car.

Other objects and advantages of my invention will be apparent from the following detailed description by referring to the accompanying drawings.

In the drawings:

Fig. 1 is a partial transverse section of a refrigerator car embodying my invention.

Fig. 2 is a view similar to a portion of Fig. 1 showing a modified form of operating operating means for the valve and also a means to provide accessibility to the valve for cleaning and repairing thereof.

Fig. 3 is a longitudinal section of the upper part of the car shown in Fig. 1 as indicated by the line 3—3 of Fig. 1.

Fig. 4 is an enlarged sectional view of the valve shown in Fig. 1.

Fig. 5 is a section on line 5—5 of Fig. 4.

Fig. 6 is a section on line 6—6 of Fig. 2.

The general parts of the refrigerator car shown are insulated roof 2, side wall 3, floor 4, hatch 5, refrigerant container 6, side wall flue 7, foraminous floor rack 8 and space 9 between rack 8 and floor 4. A refrigerant container 6 is positioned directly below the roof 2 and adjacent the side wall 3. A drip pan 12 is provided below the container 6 and a partition 14 is secured in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to the flue 7 is formed by spacing the drip pan 12 from the wall 3. Cars of this type commonly have a row of refrigerant containers 6 near each side wall 3 and spaced apart at the center of the car. The partitions 14 are also spaced apart to form a duct 16 which communicates between the lading compartment 18 and openings 15.

Air circulation is as follows: Air in the lading compartment 18 is warmed by contact with the lading and rises through the duct 16 to enter the

enclosing structures 11 through the air inlet openings 15, some of said air flowing through the passage 19 between the refrigerant container 6 and drip pan 12. The air is cooled by contact with the refrigerant containers 6 and falls by reason of its greater density through the discharge openings 17 and flues 7 to the space 9 whence it rises through the rack 8 to the lading compartment 18.

As shown in Fig. 1, the valve 25 is secured to the lower part of the refrigerant container 6, preferably the bottom 26 thereof, and also preferably at substantially the lowest part thereof, so that when the valve 25 is open all of the liquid in the container drains through the valve. The valve 25 is shown in detail in Figs. 4 and 5. An aperture 28 is provided in the bottom 26 of the refrigerant container 6 and said bottom is reinforced in the vicinity of the aperture 28, preferably by a plate 30 secured to the bottom 26, as by welding. The valve 25 comprises a casing 32 secured to the container bottom 26 by some means, such as the bolts 33, and has a substantially vertical passage 34 therethrough communicating with the aperture 28 for the flow of liquid. A substantially horizontal passage 36 intersects the vertical passage 34 and a plug 38 is fit into the horizontal passage 36 in such a way that the plug 38 is free to rotate within the horizontal passage 36. The plug 38 has a transverse aperture 40 therein adapted to be aligned or unaligned with the vertical passage 34 through the casing, depending upon whether the valve is to be open or closed. In Fig. 5, the valve is shown with the aperture 40 aligned with the passage 34, the valve being open. To close the valve, the plug 38 is rotated substantially 90 degrees or until the aperture 40 and passage 34 are unaligned. The axis of rotation of the plug 38 preferably extends substantially transversely of the car.

The plug 38 preferably has a boss 45 disposed substantially on the axis of rotation thereof and a rod 46, as shown in Fig. 1, is connected to the boss 45. The end 48 of the rod 46 may be split and spread to straddle the boss 45 and a cotter pin 50 inserted through the boss 45 and the spread ends of the rod 46 to form an operative connection between the rod 46 and the boss 45. The opposite end 52 of the rod 46 extends through an aperture 53 in the partition 14 and is provided with a handle 54 disposed within the duct 16. The handle 54 may be pivoted (56) to the rod 46 so as to hang in a depending position, thereby preventing accidental opening of the valve by a change in the position of the handle 54 due to gravitational forces.

In Fig. 2, a tubular member or a pipe 65 is shown instead of the rod 46 shown in Fig. 1. It is preferable to have a square boss 45 on the valve 25 and to flatten the end of the pipe 65 so as to fit over the square boss 45. A cotter pin 67 may be inserted to insure a positive connection. The pipe 65 extends through the partition 14 in a manner heretofore described in connection with the rod 46 shown in Fig. 1, but instead of a handle an aperture 68 is provided in the pipe 65 through which a pin may be inserted when it is desired to operate the valve. This arrangement eliminates the danger of the handle swinging during service movements of the car and thereby accidentally operating the valve.

It is sometimes necessary to clean or repair the valve 25, the operating mechanism therefor or certain parts of the refrigerant container 6. I provide, for this purpose, a drip pan 12 hinged

5 (74) to the side wall lining 75, as shown in Fig. 1, so that the drip pan 12 may be swung downwardly and the entire lower part of the container 6 made available for repairing or cleaning. In Fig. 2, an opening is provided in the drip pan 12 substantially below the valve 25 and a door 76 provided to close the opening. The drip pan 12 may be provided with depending flanges 78 and the door 76 with upstanding flanges 80 to overlap the depending flanges 78 of the drip pan 12 and thereby form a water-tight seal. A bracket 81 or any other suitable means may be provided to hold the door 76 in place.

It is pointed out that the operating rod 46 in Fig. 1 and the pipe 65 in Fig. 2 extend through an aperture 53 in the partition 14, which aperture is disposed a substantial distance above the upper surface of the drip pan 12. The drip pan 12 has a substantial slope toward the flue 7 so that liquid which overflows from the refrigerant container 6 or condenses thereon and falls upon the drip pan 12 will flow into the side wall flue 7 and not through the aperture 53 in the partition 14. It is also pointed out that the rod 46 in Fig. 1 and pipe 65 in Fig. 2 are disposed substantially parallel with the direction of air flow through the passage 19 between the container 6 and drip pan 12. The valve 25 and the operating rod 46 or pipe 65, therefore, present but a small obstacle to the flow of refrigerating air. This condition is clearly shown in Fig. 3 wherein the valve 25 and rod 46 encroach on only a relatively small part of the passage 19.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

The method of supporting the refrigerant containers disclosed herein is claimed in my co-pending application filed July 24, 1939, Serial No. 286,138.

I claim:

1. In a refrigerator car having a flue associated with a vertical wall thereof, a refrigerant container below the roof and adjacent said wall, a drip pan spaced below said container to form a passage which conducts air to said flue, a partition upstanding from said drip pan remote from said wall and means forming a duct for upward flow of warm air adjacent said partition, means for draining liquid from said container into said passage and means operable from said duct for operating said draining means.

2. In a refrigerator car having a flue associated with a vertical wall thereof, a refrigerant container below the roof and adjacent said wall, a drip pan spaced below said container to form a passage which conducts air to said flue and means forming a duct for upward flow of warm air adjacent said container, means for draining liquid from said container into said passage and means operable from said duct for operating said draining means.

3. In a refrigerator car having a flue associated with a vertical wall thereof, a refrigerant container below the roof and adjacent said wall, a drip pan spaced below said container to form a passage which conducts air to said flue and means forming a duct for upward flow of warm air adjacent said container, means for draining liquid from said container into said passage comprising a valve associated with the bottom of

said container on the exterior thereof, said valve comprised of a casing having an opening therethrough and a plug adapted to open and close said opening upon rotation thereof and means operable from said duct for rotating said plug.

4. In a refrigerator car having a flue associated with a vertical wall thereof, a refrigerant container below the roof and adjacent said wall, a drip pan spaced below said container to form a passage which conducts air to said flue and means forming a duct for upward flow of warm air adjacent said container, means for draining liquid from said container into said passage comprising a valve associated with said container adapted to be opened and closed by rotation of a plug and means operable from said duct for rotating said plug.

5. In a refrigerator car having a flue associated with a vertical wall thereof, a refrigerant container below the roof and adjacent said wall, a drip pan spaced below said container to form a passage which conducts air to said flue, a partition upstanding from said drip pan remote from said wall and means forming a duct for upward flow of warm air adjacent said partition, means for draining liquid from said container into said passage comprising a valve associated with the bottom of said container on the exterior thereof remote from said duct, said valve comprised of a casing having an opening therethrough and a plug adapted to open and close said opening upon rotation thereof on an axis transverse to said wall and means operable from said duct for rotating said plug comprising a rod within said passage engaged with said plug and extending through said partition into said duct and means disposed in said duct to rotate said rod.

6. In a refrigerator car having a flue associated with a vertical wall thereof, a refrigerant container below the roof and adjacent said wall, a drip pan spaced below said container to form a passage which conducts air to said flue, a partition upstanding from said drip pan remote from said wall and means forming a duct for upward flow of warm air adjacent said partition, means for draining liquid from said container into said passage comprising a valve associated with the bottom of said container on the exterior thereof remote from said duct, said valve comprised of a casing having an opening therethrough and a plug adapted to open and close said opening upon rotation thereof on an axis transverse to said wall and means operable from said duct for rotating said plug comprising a rod within said passage engaged with said plug and extending through said partition into said duct and means disposed in said duct to rotate said rod, said last mentioned means comprising a handle pivoted to said rod.

7. In a refrigerator car having a flue associated with a vertical wall thereof, a refrigerant container below the roof and adjacent said wall, a drip pan spaced below said container to form a passage which conducts air to said flue, a partition upstanding from said drip pan remote from said wall and means forming a duct for upward flow of warm air adjacent said partition, means for draining liquid from said container into said passage comprising a valve associated with the bottom of said container on the exterior thereof remote from said duct, said valve comprised of a casing having an opening therethrough and a plug adapted to open and close said opening upon rotation thereof on an axis transverse to said wall and means operable from said duct for ro-

tating said plug comprising a rod within said passage engaged with said plug and extending through said partition into said duct and means disposed in said duct to rotate said rod, said last mentioned means comprising an aperture through said rod and a pin removably inserted in said aperture.

8. In a refrigerator car having a flue associated with a vertical wall thereof, a refrigerant container below the roof and adjacent said wall and an enclosing structure for said container substantially closed except for a cold air discharge opening leading to said flue and an air inlet opening at a higher elevation than the discharge opening, said structure being spaced from the container to provide a passage for air flow from said inlet to said discharge opening, means for draining liquid from said container comprising a valve associated with said container adapted to be opened and closed by rotation of a plug and means to operate said draining means from the exterior of said enclosing structure, said last mentioned means comprising a rod engaged with said plug and extending parallel with said air flow.

9. In a refrigerator having a roof and a wall, a flue associated with said wall, a refrigerant container below said roof and adjacent said wall, an enclosure for said container arranged to cooperate therewith to form a passage which communicates with said flue, means to direct a flow of air through said passage and said flue, a valve associated with the lower part of said container for draining therefrom the contents thereof, and means extending through said passage for operating said valve from exterior of said enclosure.

10. In a refrigerator having a roof and a wall, a flue associated with said wall, a refrigerant container below said roof and adjacent said wall, an enclosure for said container arranged to cooperate therewith to form a passage which communicates with said flue, means to direct a flow of air through said passage and said flue, a valve associated with the lower part of said container for draining therefrom the contents thereof, and means extending through said passage for operating said valve from exterior of said enclosure, said last mentioned means arranged to leave said passage substantially unrestricted for air flow.

11. In a refrigerator having a roof and a wall, a flue associated with said wall, a refrigerant container below said roof and adjacent said wall, an enclosure for said container, a passage adjacent said container which communicates with said flue, means to direct a flow of air through said passage and said flue, a valve associated with the lower part of said container for draining therefrom the contents thereof, and means extending through said passage for operating said valve from exterior of said enclosure, said last mentioned means arranged to leave said passage substantially unrestricted for air flow.

12. In a refrigerator having a roof and a wall, a flue associated with said wall, a refrigerant container below said roof and adjacent said wall, an enclosure for said container arranged to cooperate therewith to form a passage which communicates with said flue, means to direct a flow of air through said passage and said flue, a valve associated with the lower part of said container for draining therefrom the contents thereof, and a rod for operating said valve extending through a portion of said passage to the exterior of the enclosure, said rod being substantially parallel with

the direction of air flow through said passage for the purpose specified.

13. In a refrigerator having a roof and a wall, a flue associated with said wall, a refrigerant container below said roof and adjacent said wall, an enclosure for said container, a passage adjacent said container which communicates with said flue, means to direct a flow of air through said passage and said flue, a valve associated with the lower part of said container for draining therefrom the contents thereof, and a rod for operating said valve extending through a portion of said passage to the exterior of the enclosure, said rod being substantially parallel with the direction of air flow through said passage for the purpose specified.

14. In a refrigerator car having a flue associated with a vertical wall thereof, a refrigerant container below the roof and adjacent said wall, an enclosure for said container, a passage adjacent said container which communicates with said flue to provide, in combination therewith, a conduit for flow of air, means forming a duct adjacent said container for upward flow of warm air, means associated with said container to discharge the contents thereof into said conduit, and means operable from said duct for operating said discharging means.

15. In a refrigerator car having a flue associated with a vertical wall thereof, a refrigerant container below the roof and adjacent said wall, a drip pan spaced below said container to form a passage which communicates with said flue to provide, in combination therewith, a conduit for flow of air, means forming a duct adjacent said container for upward flow of warm air, means associated with said container to discharge the contents thereof into said conduit, an opening in said drip pan below said discharging means, a door adapted to close said opening, and means operable from said duct for operating said discharging means.

16. In a refrigerator car having a flue associated with a vertical wall thereof, a refrigerant container below the roof and adjacent said wall, an enclosure for said container, a passage adjacent said container which communicates with said flue to provide, in combination therewith, a conduit for flow of air, means forming a duct adjacent said container for upward flow of warm air, means associated with said container to discharge the contents thereof into said conduit, comprising a valve adapted to be opened and closed upon rotation of a plug, a rod operatively connected to said plug and extending into said duct, and a handle in said duct operatively connected near one end of the handle to said rod, said handle arranged to depend from said rod when the valve is closed.

17. In combination with the walls, roof and floor of a refrigerator car, a refrigerant container below the roof, an enclosure for said container, said car having a lading compartment enclosed by said walls, floor and the lower part of said enclosure, a duct arranged to provide a path for air flow from the upper part of said lading compartment to the upper part of said enclosure, means for discharging the contents from said container, and means operable from said duct for operating said first mentioned means.

18. In combination with the walls, roof and floor of a refrigerator car, a pair of refrigerant containers below the roof, enclosures for said containers, said car having a lading compartment enclosed by said walls, floor and the lower parts of said enclosures, said enclosures being spaced apart to form a duct arranged to provide a path for air flow from the upper part of said lading compartment to the upper parts of said enclosures, means for discharging the contents from one of said containers, and means operable from said duct for operating said first mentioned means.

CHARLES D. BONSALL.
